UNITED STATES PATENT OFFICE

2,424,840

DRAFTING APPARATUS

William H. Murphy, Chicago, Ill.

Application April 10, 1944, Serial No. 530,243

6 Claims. (Cl. 33—80)

1

My invention relates generally to drafting apparatus and more particularly to improved apparatus of this character having a universally adjustable head mounted for transverse movement on a mobile straightedge.

It is an object of my invention to provide an improved drafting apparatus which may be easily adjusted to facilitate drawing lines at any desired angle and at any position upon the drafting board or table.

A further object is to provide an improved drafting apparatus which is very simple in construction and may be produced at a much lower cost than comparable apparatus made in the past.

Other objects will appear from the following description, reference being had to the accompanying drawings, in which.

Fig. 1 is a plan view of a drawing board with the improved apparatus of my invention installed thereon;

Fig. 2 is an enlarged plan view of a slightly modified form of the invention, in that the protractor head is provided with but a single arm;

Fig. 3 is a rear plan view of a portion of the apparatus shown in Fig. 2;

Figs. 4 and 5 are enlarged sectional views taken on the lines 4—4 and 5—5, respectively, of Fig. 2;

Fig. 6 is a fragmentary sectional view taken on the line 6—6 of Fig. 4 and showing the head clamping means in clamping position; and

Fig. 7 is a view similar to Fig. 6, showing the parts of the clamping mechanism in released position.

Referring to Fig. 1, the apparatus of my invention is illustrated as being mounted upon a drafting board, or table, 10, which may be of any suitable construction, and which is equipped with a mobile straightedge 12. This straightedge is preferably of the general construction shown in the patent to H. L. De Lisle, No. 2,256,241. As shown in greater detail in said patent, the mobile straightedge 12 is constrained for translatory movement by means of cables 14 and 16, the ends of which are joined by a spring slack take-up device 18, and the opposite ends of which are respectively anchored to the board or table 10 at the lower edge thereof. The cable 16 passes around a pulley 20 which includes a suitable cable clamp 22 normally engaged with the cable to prevent movement of the cable 16 around the pulley 20.

When it is desired to have the straightedge 12 positioned at an angle to the horizontal edge of the board 10, the clamp 22 may be released and

2

the straightedge 12 then adjusted to the desired angle, whereupon the clamp 22 is reengaged. Thereafter, the straightedge 12 will be translatable upwardly and downwardly on the board 10, but will maintain the set angularity with respect to the horizontal edge of the board.

As best shown in Figs. 4 and 5, the straightedge 12 comprises a strip 24 of a suitable non-warping plastic material, such as "Formica XX," 10 with a raised shoulder portion 24a which is shown as formed of a separate strip of material cemented thereto and upon which a complementary strip 26 is secured by a plurality of drive screws 28. The edges of the strip 24 are grooved for 15 the reception of transparent plastic ruler edges 30, 31, which may be secured in place by a suitable adhesive. The contacting faces of the strips 24a and 26 are provided with opposed grooves forming a passageway 34 for the operating cables 20 14 and 16.

The longitudinal edges of the strip 26 are undercut to provide way or guide surfaces for complementally beveled washers 36 secured to a protractor body 38 by screws 40, and for engagement 25 by a clamping bar 42 having a beveled edge 44. A strip or shoulder 24a is reversely and complementarily beveled on its longitudinal edges with respect to the undercut edges of strip 26, and in the form illustrated is extended laterally slightly 30 beyond the meeting edges of strip 26. The clamping bar 42 is mounted for lateral sliding movement with respect to the protractor body 38 by means of a pair of rivets 46 which are laterally slidable in slots 48. As best shown in Figs. 35 6 and 7, the bar 42 is pressed against the beveled edge of the strip 26 by a bowed wire spring 50, the ends of which fit in suitable sockets 52 formed in the bar 42, and the central portion of which reacts against a screw 54.

40 The bar 42 is adapted to be moved laterally to cause its beveled edge 44 to be disengaged from the adjacent under-cut edge of the strip 26 sufficiently to permit removal of the protractor head 38 from the straightedge. The means for accomplishing such movement of the bar 42 comprises a manually operable lever 56 secured to a crank-shaft 58 mounted for pivotal movement in the head 38. The crank portion of the shaft 58 projects into a longitudinal slot 60 formed in the bar 42 so that upon rotation of the lever 56 from its 45 normal horizontal position (Fig. 2) to a substantially vertical position (Fig. 7), the bar 42 is moved laterally against the resilient force of the spring 50 a sufficient distance to free the edge 44 of the clamping bar 42 from the adjacent under-

cut beveled edge of the strip 26 of the straight-edge. When the clamping bar 42 is moved to this position, as shown in Fig. 7, the protractor head may be removed from the straightedge.

The body 38 of the protractor head is drilled to receive a headed socket member 62 which is internally threaded to receive a stud 64 which may be molded as an insert in a knob 66. The movable part 68 of the protractor is pivoted on the socket 62 and is frictionally clamped to the body 38 by an undercut washer 70. The protractor part 68 fits closely in a complementary recess 72 formed in the upper surface of the body 38, and the upper surface of the protractor part 68 has angular degree graduations 74 marked thereon in a suitable manner, these graduations cooperating with vernier graduations 76 marked on the upper surface of the body 38 adjacent the graduations 74.

The protractor part 68 may be provided with a single arm 78 as shown in Figs. 2 and 3, or may have a pair of mutually perpendicular arms 80. In each instance, the arms 78 and 80 are provided with suitable dovetail slots for the reception of complementary parts on ruler arms 82, so that the latter may be detached whenever desired.

From a consideration of the fact that the mobile straightedge 12 may be adjusted for translatory movement while at any desired inclination to the horizontal, it will be clear that the apparatus may be used with great convenience in the making of drawings having a non-horizontal base line. In making such drawings, the mobile straightedge 12 is adjusted to lie parallel to the base line and the apparatus may then be used to draw lines at predetermined angles with respect to the base line, by setting the protractor part 68 at such angle with respect to the "0" mark of the vernier graduations 76. The making of drawings of this type is thus facilitated as compared with making them with a conventional drafting machine, in that all angular dimensions may be read directly from the graduations 74, whereas in the conventional drafting machine such angular dimensions would have to be computed from the scale reading of the machine by adding or subtracting the angle by which the base line deviates from the horizontal.

The spring 50, through the bar 42, secures the body 38 of the protractor head firmly to the straightedge so that it will not tilt relative thereto, and applies sufficient clamping force to produce friction between the bar 42 and the strip 26 so that the head will not be liable to accidental displacement from the position on the straightedge 12 to which it is set. Whenever the protractor head is not to be used it may readily be disengaged from the straightedge 12 merely by swinging the wing lever 55 to a vertical position, whereupon the bar 42 will be moved out of the undercut bevel of the straightedge sufficiently to permit the protractor head to be raised and removed from the straightedge 12. Similarly, the head may be easily and quickly attached to the straightedge.

While I have shown and described particular embodiments of my invention, it will be apparent that numerous variations and modifications thereof may be made without departing from the underlying principles of the invention. I therefore desire, by the following claims, to include within the scope of my invention, all such variations and modifications by which substantially the results of my invention may be obtained

through the use of substantially the same or equivalent means.

I claim:

1. In combination, a straight-edge having under-cut longitudinal edges, a protractor member slidably mounted on said straight-edge and having retaining members engaging beneath one of said under-cut edges and an engaging member slidably mounted upon said protractor head and provided with means movable into and out of position engaging beneath the other of said under-cut edges.

2. In combination, a straight-edge having under-cut longitudinal edges, a protractor member slidably mounted on said straight-edge, and having retaining members engaging beneath one of said under-cut edges, an engaging member slidably mounted upon said protractor head and provided with means movable into and out of position engaging beneath the other of said under-cut edges, and spring means coacting with said last named member to urge the same into engaging position.

3. In combination, a straight-edge having under-cut longitudinal edges, a protractor member slidably mounted on said straight-edge, and having retaining members engaging beneath one of said under-cut edges, an engaging member slidably mounted upon said protractor head and provided with means movable into and out of position engaging beneath the other of said under-cut edges, spring means coacting with said last named member to urge the same into engaging position, and means manually operable to retract said last named member against the action of said spring to permit disengagement of said protractor from said straight-edge.

4. A straight-edge, a protractor slidably mounted thereon, said straight edge being provided with under-cut longitudinal edges, said protractor being provided with retaining members engageable beneath one of said under-cut edges, said protractor member additionally being provided with slots, securing members slidably mounted in said slots and headed at one end to prevent disengagement from said protractor member, an engaging member carried by said securing members at their opposite ends and movable into and out of position engaging beneath the other of said under-cut edges, and means yieldingly urging said securing member in engaging position.

5. A straight-edge, a protractor slidably mounted thereon, said straight-edge being provided with under-cut longitudinal edges, said protractor being provided with retaining members engageable beneath one of said under-cut edges, said protractor member additionally being provided with slots, securing members slidably mounted in said slots and headed at one end to prevent disengagement from said protractor member, an engaging member carried by said securing members at their opposite ends and movable into and out of position engaging beneath the other of said under-cut edges, means yieldingly urging said securing member in engaging position, said last named means comprising a spring member and a pin coacting therewith and carried by said protractor member.

6. A straight edge, a protractor slidably mounted thereon, said straight edge being provided with under-cut longitudinal edges, said protractor being provided with retaining members engageable beneath one of said under-cut edges, said protractor member additionally being pro-

vided with slots, securing members slidably mounted in said slots and headed at one end to prevent disengagement from said protractor member, an engaging member carried by said securing members at their opposite ends and movable into and out of position engaging beneath the other of said under-cut edges, means yieldingly urging said securing member in engaging position, and means to disengage said engaging member comprising a manually operable eccentric member carried by said protractor member and engaging said engaging member.
